UNITED STATES PATENT OFFICE.

FREELAND D. LESLIE, OF MILTON, MASSACHUSETTS, ASSIGNOR TO B R E MANUFACTURING COMPANY, OF HYDE PARK, MASSACHUSETTS, A CORPORATION OF MASSACHUSETTS.

HINGE.

Application filed October 15, 1921, Serial No. 507,883.

To all whom it may concern:

Be it known that I, FREELAND D. LESLIE, a citizen of the United States of America, and a resident of Milton, in the county of Norfolk and State of Massachusetts, have invented certain new and useful Improvements in Hinges, of which the following is a specification.

This invention relates to hinges and particularly to that class of hinges which are used to connect the seat and cover to water closet hoppers.

The principal object of the invention is the production of a hinge which may be covered with white enamel and is so constructed that the enamel will not become injured or worn when either the seat or cover is being moved about the axis of the hinge pin.

20 The invention consists primarily in casting a tubular member into the ears of the cover hinge leaf, said tubular member surrounding another tubular member, the ends of which are threaded to the posts extending upwardly from the rear part of the hopper.

The invention further consists in certain novel features of construction and arrangement of parts which will be understood by 30 reference to the description of the drawings and to the claims to be hereinafter given.

For the purpose of illustrating the invention, one preferred form thereof is illustrated in the drawings, this form having been found to give satisfactory and reliable results although it is to be understood that the various instrumentalities of which the invention consists can be variously arranged 40 and organized and the invention is not limited to the precise arrangement and organization of these instrumentalities as herein shown and described except as required by the scope of the appended claims.

45 Of the drawings:

Figure 1 represents a side elevation of a portion of a water closet hopper with a hinge embodying the principles of the present invention applied thereto.

50 Figure 2 represents a plan of the rear of the same.

Figure 3 represents a section on line 3, 3, on Fig. 1, and

Figure 4 represents a section on line 4, 4, on Fig. 2.

Figures 3 and 4 are drawn to an enlarged scale.

Similar characters indicate like parts throughout the several figures of the drawings.

In the drawings, 10 is a hopper for water closets having rearwardly extending ears 11, each ear 11 having a vertical hole 12 therein in which is disposed the threaded shank 13 of a standard or post 14, the upper end of which is curved laterally as indicated in Fig. 1 of the drawings.

Threaded to each shank 13 is a nut 15, the edge of which is provided with an annular flange 16 which is adapted to bear 70 against the upper face of one of the ears 11.

The lower end of each shank 13 has threaded thereto a clamping nut 17, the outer end of which is closed as indicated at 18.

Between each clamping nut 17 and the under face of the ear 11 is a cup-shaped washer 19.

Each nut 15 is provided with a tubular extension 20 which surrounds the lower end 80 of the unthreaded portion of the standard or post 14.

This extension 20 is of sufficient length to permit the nuts 15 and 17 to be adjusted relatively to the threaded shank 13 to suit 85 various conditions without the extension 20 uncovering the unthreaded portion of the posts or standards 14.

By making this extension 20 in this manner and making the clamping nut with a 90 closed end, the connection between the hopper and the main part of the hinge is greatly improved in appearance and more sanitary.

The upper ends of the standards 14 are provided with threaded sockets 21 in which 95 are secured the opposite threaded ends of a cylindrical supporting member 22 interposed between said standards or posts 14.

The seat 23 has secured to its under face a hinge leaf 24 having rearwardly extending ears 25 which are preferably parallel.

The ears 25 each have a cylindrical open-

ing therein through which the cylindrical member 22 extends.

The cover 26 has secured to its under face a hinge leaf 27 having rearwardly-extending parallel arms 28.

Interposed between said arms 28 and extending through the same is a tubular member 29 surrounding the cylindrical supporting member 22.

10 This cylindrical supporting member 22 is preferably made tubular thereby lessening the weight and reducing the cost of material.

15 The tubular member 29 has its opposite ends preferably cast into the rear ends of the rearwardly-extending arms 28 of the hinge leaf 27 and therefore is secured to the arms in such a manner as to cause it to move about the axis of the cylindrical supporting member 22 whenever the cover 26 is raised or

20 lowered.

During this movement of the cover, the supporting member 22 is not moved, the ends thereof being fixedly secured in the posts 14.

25 Surrounding the tubular member 22 and interposed between the posts or standards 14, the ears 25 and the arms 28, are a plurality of washers 30 preferably of celluloid or some similar non-metallic material, these 30 washers preventing the adjacent metal faces of the parts of the hinge from contacting with each other.

35 While in the drawings the curved portion of the standards or posts 14 are shown curved upwardly toward the front of the hopper, the various parts of the hinge and its supporting member may be readily disassembled and again assembled with the curved portions of these standards or posts 14 extending to the 40 rear of the hopper.

This makes it possible to utilize the same hinge for various forms of hoppers.

One of the principal objects of the present invention is to provide a hinge which may be 45 covered with white enamel and which may be used without the movable parts wearing away the enamel on the standing parts.

Heretofore in most hinges for water closets, the construction is such that the 50 movable parts of the hinge wear away the enamel or the nickel on the standing parts and soon leaves unfinished portions which present an unsightly appearance.

55 By means of the present construction these objections are wholly overcome for both hinge leaves 24, 27, the tubular member 29 and the posts or standards 14 may be covered with white enamel and inasmuch as the tubular member 29 always moves with the 60 hinge leaf 27 upon the tubular member 22, any wearing on said tubular member will never be exposed to view.

The washers 30 of celluloid or some other construction prevent the wearing of the adja-

cent metal faces of the hinge and these 65 washers may be made of various thicknesses to permit the adjustment of the posts 14 relatively to each other in order to accommodate the hinge to various forms of hoppers.

In hoppers on which no cover is used the 70 tubular member 29 has its ends cast into the ears 25 of the seat hinge 24.

It is believed that the operation and many 75 advantages of the invention will be understood without further description.

Having thus described my invention, I claim

1. A hinge leaf having parallel arms; a separate tubular member interposed between said arms with its ends secured therein; a cylindrical member extending through and beyond the ends of said tubular member; and standards having sockets to receive the opposite ends of said cylindrical member adjustably secured thereto.

2. A hinge leaf having parallel arms; a tubular member interposed between said arms with its ends secured therein; a cylindrical member extending through and beyond the ends of said tubular member; said cylindrical member having its opposite ends threaded and standards having threaded sockets to receive the opposite threaded ends of said cylindrical member.

3. A hinge leaf having parallel arms; a separate tubular member interposed between said arms with its ends cast therein; a cylindrical member extending through and beyond the ends of said tubular member; and standards having sockets to receive the opposite ends of said cylindrical member.

4. A hinge leaf having parallel arms; a separate tubular member interposed between said arms with its ends secured therein; a cylindrical member extending through and beyond the ends of said tubular member; standards in which the ends of said cylindrical member are adjustably secured; and a second hinge leaf having perforated ears interposed between said arms and standards 110 and through which said cylindrical member extends.

5. A hinge leaf having parallel arms; a separate tubular member interposed between said arms with its ends secured therein; a cylindrical member extending through and beyond the ends of said tubular member; standards in which the ends of said cylindrical member are secured; a second hinge leaf having perforated ears interposed between 115 said arms and standards and through which said cylindrical member extends; and non-metallic washers surrounding said cylindrical member between the opposing faces of said standards, ears and arms.

6. A hinge having parallel arms; a tubular member interposed between and secured to said arms; a cylindrical member extend-

ing through and beyond the ends of said tubular member; standards having threaded lower ends; a nut on the lower end of each standard and having a tubular extension 5 surrounding the unthreaded end of said standard; and a clamping nut also mounted on each threaded end.

Signed by me at 746 Old South Bldg., Boston, Mass., this 11th day of October, 1921.

FREELAND D. LESLIE.
